ASH RECEIVER

Helene Crawford, Silverton, Colo.

Application February 28, 1939, Serial No. 259,056

1 Claim. (Cl. 220—69)

The invention relates to an ash receiver or receptacle and more especially to a pocket ash receptacle for smokers' use.

The primary object of the invention is the provision of a receptacle of this character, wherein cigarette or cigar ashes can be conveniently dropped therein and such receptacle is susceptible of fastening on a belt worn by a person or placed upon a support or carried within the pocket of such person, being convenient for use at the option of the possessor thereof.

Another object of the invention is the provision of a receptacle of this character, wherein the construction thereof is novel and is self-closing so as to exclude odor therefrom in the use for collecting ashes dropped therein from a cigar or cigarette as well as the spent cigar or cigarette, being readily cleaned and is of a size for the convenient carrying thereof upon the person or occupying minimum space when upon a support.

A further object of the invention is the provision of a receptacle of this character, which is simple in its construction, thoroughly reliable and efficient in operation, convenient for easy handling thereof, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a perspective view of a receptacle constructed in accordance with the invention shown attached to a belt, the receptacle being shown in full lines and a portion of the belt by dotted lines.

Figure 2 is a side elevation.

Figure 3 is an edge elevation.

Figure 4 is a top plan view.

Figure 5 is a view similar to Figure 2 looking toward the opposite side of the receptacle.

Figure 6 is an enlarged side elevation partly in section, the section being taken on the line 6—6 of Figure 3 looking in the direction of the arrows.

Figure 7 is an enlarged sectional view taken on the line 7—7 of Figure 2 looking in the direction of the arrows.

Similar reference characters indicate corresponding parts throughout the several views in the drawing.

Referring to the drawing in detail, the recep-

tacle constituting an ash receiver comprises a box-like body 10, in this instance of circular shape although it may be otherwise shaped, having a permanently closed side 11 while the opposite open side is closed by a hinged lid or cover 12, the hinge being indicated at 13, while a snap latch 14 fastens the said lid or cover in closing position relative to the open side of the body 11. This lid or cover when opened allows convenient cleaning of the receptacle or the dumping of the 10 contents therefrom.

In the peripheral wall 15 of the said body is an elongated substantially rectangular shaped opening 16 for the passage of ashes from a cigar or cigarette for deposit within the receptacle 15 while interiorly of said body 11 following opposite side edges of the opening 16 and located at the inner face of the peripheral wall 15 are channeled guides 18 for a closing shutter 17 slidably fitting said channeled guides and curved corresponding to the peripheral wall 15.

The shutter 17 is formed with an eye 18 at the inner side thereof with which loosely engages the attaching end 19 of a wire spring 20, being formed with a tensioning coil 21 fixed at 22 to 25 the permanent side 11 of the body 10. This spring 20 urges the shutter 17 to an opening position. In a complete closed position the shutter 17 is engaged by a finger-operated releasing latch 23 carried by the peripheral wall 15 and having 30 the protruding push button 24 exposed outwardly of said body 10. The shutter 17 under the action of the spring 20 automatically moves to open position clearing the slot or opening 16 so that ashes can be dropped into the body 10. When the 35 shutter is shifted to a closed position, it is latched in such position with relation to the slot or opening 16.

Mounted exteriorly on the permanent side 11 of the body 10 is a hanger clip 25 enabling the receptacle to be engaged upon a belt, a portion 40 thereof being indicated at 26, adapted to be worn by a person.

The body 10 has normally fitted in countersinks 27 provided in the side 11 and lid or cover 12 foldable rest members 28, these being hinged at 29, and are adapted to be extended for supporting the body 10 in a perpendicular position with the slot or opening 16 uppermost and in this manner the receptacle can be used upon a support or the like. The members 28 are foldable for seating within the countersinks 27 to be flush with the outer surfaces of the side 11 and lid or cover 12, respectively, so that the receptacle may be conveniently carried within the pocket of a 55

garment, the position of the members 28 for the holding of the receptacle upon a support being shown in Figure 7 of the drawing.

What is claimed is:

- 5 An ash receiver of the character described, comprising a substantially cylindrical body having opposite flat walls provided with matched indentations meeting the periphery of said body,

disklike pieces received by the indentations for lying flush with the outer surfaces of the flat sides, and hinges joining the said pieces with the said body at the periphery thereof for the outward swinging of said pieces to a plane common to each other and flush with the outer periphery of the said body. 5

HELENE CRAWFORD.
